DUAL PURPOSE SUCTION NOZZLE

Gustaf Einar Lofgren, Riverside, Conn., assignor to Electrolux Corporation, Old Greenwich, Conn., a corporation of Delaware

Application July 19, 1954, Serial No. 444,003

4 Claims. (Cl. 15—339)

My invention relates to cleaning tools for vacuum cleaners and more particularly to a dual purpose tool, that is, a tool provided with two different types of suction nozzles thereon which may be used selectively in order to clean different kinds of surfaces.

More particularly my invention relates to a combination rug nozzle and floor brush. It is highly desirable that such a tool be made as low as possible in order that it may be used to clean underneath low furniture such as beds, sofas and the like. It has long been known to provide a tool of this nature with a swivel mounting on a suction conduit so that the tool merely may be turned over when it is desired to change from one type of nozzle to the other, as for instance is shown in Patent No. 1,849,515 issued March 15, 1932 to Lars Ell. However, in order to have the necessary cross-sectional area of the suction conduit, the diameter of this conduit must be such as to require an overall height of the tool which is greater than desirable, particularly when one of the tools is a floor brush nozzle which itself must have a greater vertical dimension than a rug nozzle because of the length of the brush bristles.

In accordance with my invention a substantial reduction in the height of the tool is obtained without reducing the cross-sectional area of the suction conduit by making the latter flat or oblong with its minor axis extending in a vertical direction. This of course prevents the tool from being rotatably mounted on the suction conduit, and in order to change from one type of nozzle to the other the tool is removed from the suction conduit, turned over and again connected to the conduit.

Further objects and advantages of my invention will be apparent from the following description when taken in connection with the accompanying drawings which form a part of the specification and in which:

Fig. 1 is a top view of a preferred embodiment of my invention with the rug nozzle in operative position;

Fig. 2 is a front view of the nozzle shown in Fig. 1;

Fig. 3 is a cross-sectional view taken on the line 3—3 of Fig. 1;

Fig. 4 is a bottom view of the nozzle shown in Fig. 1;

Fig. 5 is a cross-sectional view taken on the line 5—5 of Fig. 1;

Fig. 6 is a cross-sectional view similar to Fig. 5, but with the cleaning tool removed from the suction conduit;

Fig. 7 is a cross-sectional view similar to Fig. 5, but with the cleaning tool connected to the conduit with the floor brush in operative position; and

Fig. 8 is a cross-sectional view taken on the line 8—8 of Fig. 5.

Referring more particularly to the drawings, reference character 10 designates generally a cleaning tool on opposite faces of which are formed a floor brush nozzle 12 and a rug nozzle 14. As shown, the tool 10 includes a casting 16 of metal or plastic. Secured to one face of the casting 16 by means of screws 18 is a stamping or the like 20 which is formed with a central opening 22.

2

The lengthwise edges of the stamping are formed as channels 24 which are received within grooves 26 formed in the casting 16. Strips of bristles 28 are received in these channels and may be retained in place therein by the outer flanges 30 of the channels being crimped inwardly. The stamping 20 and the bristles 28 together constitute the floor brush portion of the cleaning tool.

Secured to the opposite face of the casting 16 by means of screws 32 is a pair of glider pads 34. Clamped between these pads and the casting along the forward edge of the latter is a stamping 36 which constitutes the forward lip of the rug nozzle. As shown, this stamping may be formed with a rib portion 38 adjacent to each end and transverse ribs 40 near the central portion. Also retained in place by means of the pads 34 is a rod 42 which is cylindrical on one side and formed with teeth 44 on the other. This rod is rotatably mounted and may be turned by means of a handle 46 secured to one end thereof and received in a recess 48 formed in casting 16. This rod constitutes the rear lip of the rug nozzle.

As is seen more clearly in Figs. 5 through 7, the casting 16 is formed with a passageway 50 which extends from the opening 22 in the floor brush to an opening 52 formed in a face of the casting 16 which is intermediate of the faces on which are formed the rug nozzle and floor brush, respectively. As is seen more particularly in Fig. 2 the opening 52 is substantially flattened with its minor axis extending in the direction normal to the faces on which the suction nozzles are formed, and moreover, the opening is asymmetric with reference to a horizontal axis extending centrally of the opening and lying in the plane thereof.

The casting 16 is formed with a similar passageway 54 which extends from within the space bounded by the lips 36 and 42 of the rug nozzle to the other intermediate face of the casting, where it terminates in an opening 56. This opening is of the same size and shape as opening 52, but reversely positioned with respect thereto, as will be seen from a comparison of Fig. 2 with Fig. 3, that is, the long side of the opening 56 is adjacent to the rug nozzle face of the tool, while the long side of opening 52 is adjacent to the floor brush face.

Reference character 60 designates generally a suction conduit having an end portion 62 the cross-section of the outer surface of which is of the same size and shape as the openings 52 and 56 and is adapted to be received selectively in either of these openings. Rotatably mounted in the other end of suction conduit 60 is an elbow 64 which is adapted to be connected to a source of suction, as by means of the usual wand and flexible hose of a vacuum cleaner.

It will be noted that the flattened end section 62 of the suction conduit is eccentrically arranged with respect to the circular portion of the conduit which receives the elbow 64. In other words, this circular part of the conduit extends further to one side of the flattened end section than it does to the other side. Extending from the former side of the suction conduit is a pair of spaced projections 66. As will be seen from Figs. 5 and 7, these projections extend a sufficient distance laterally from the conduit so as to extend beyond either the floor brush bristles 28 or the rug nozzle lips 36 and 42 when the suction nozzle is connected to the openings 56 or 52, respectively. The reason for this will appear hereinafter. Pivotedly mounted between the projections 66 is a spring biased hook or latch 68. Casting 16 is formed with a pair of recesses 70 and 72 which provides surfaces engageable by the hook or latch 68 when the portion 62 of the suction conduit is received in the openings 52 or 56, respectively, so as to firmly secure the suction conduit in place.

The above described combination tool operates as follows:

With the parts in the position shown in Figs. 1 through 5, that is with the end section 62 of the suction conduit received in the opening 56, it will be seen that the passageway 54 leading from the rug nozzle is placed in communication with the suction conduit 60 and with the elbow 64 which is connected to a source of suction. Consequently, the tool may be used to clean rugs, carpets and similar soft floor covering and if it is desired to clean underneath low furniture the elbow 64 may be swiveled approximately 90° so as to lower the wand connected thereto to a position substantially parallel to the floor. The overall height of the nozzle being only slightly greater than the diameter of the elbow 64, the tool may be passed under very low furniture so as to clean the floor covering thereunder without making it necessary to move the furniture.

Due to the fact that the elbow 64 is rotatably connected to the suction conduit 60, it would be possible for the suction conduit and nozzle to be rotated 180° from the position shown in Fig. 5 so that the floor brush would be on the floor and the rug nozzle would be up in the air. Under these conditions, all of the air would still pass through the passageway 54 from the rug nozzle and would do no cleaning whatsoever. In order to guard against the possibility of the nozzle being improperly placed in this condition, the projections 66 are made to extend beyond the bristles so that if the operator attempts to incorrectly position the nozzle, the projections will strike the floor and thus indicate to the operator that the nozzle is incorrectly positioned.

When it is desired to use the floor brush for cleaning hardwood floors or hard surface floor coverings, the latch 68 is pivoted to the position shown in Fig. 6 and the end 62 of the suction conduit withdrawn from the opening 56. The cleaning tool 10 is then turned through 180° about its longitudinal axis so as to bring the opening 52 in line with the end of the suction conduit, whereupon the end section 62 of the latter is inserted into the opening 52, as is shown in Fig. 7. In this position communication is established through the passageway 50 from the floor brush to the suction conduit.

As above pointed out, the openings 52 and 56 are asymmetrical. If the openings, and the end section 62 of the suction conduit were symmetrical it would be possible to put the parts together in an improper position. Thus, it would be possible to remove the cleaning tool 10 from its connection with the suction nozzle, as shown in Fig. 5, turn the cleaning tool 180° about its lateral axis so as to bring the floor brush face of the tool into operative position with respect to the floor and then insert the end section 62 back into the same opening 56. However, if this were done the suction would be applied to the rug nozzle which now would be off the floor and hence no cleaning would result. By making the openings 52 and 56 asymmetrical, it is impossible to improperly connect the parts together.

It will thus be seen that I have provided a combination tool which may be readily changed from one type of nozzle to the other and which has a very small vertical

dimension, thus making it usable under very low furniture. While I have shown and described one preferred embodiment of my invention, it is to be understood that this has been done for purposes of illustration only and the scope of my invention is not to be limited thereby, but is to be determined from the appended claims.

What I claim is:

1. In a vacuum cleaner tool, a tubular elbow, a suction conduit attached to said elbow by a swivel joint, a nozzle member having dissimilar surface contacting faces located on opposite sides thereof and with air passages leading one from each of said faces and terminating in flattened openings at substantially the same level in opposite intermediate faces of said nozzle member whereby said tool is of relatively low height, each of said flattened openings being asymmetrical in design, with reference to a horizontal axis extending centrally of the opening and lying in the plane thereof, and of the same size and shape as the other but disposed reversely with respect to each other, said suction conduit having an end portion corresponding in size and shape to each of said openings and selectively engageable with either of said openings so that the proper surface contacting face of said nozzle member will be in communication with said suction conduit.
2. In a vacuum cleaner tool, a tubular elbow, a suction conduit attached to said elbow by a telescopic swivel joint, a nozzle member having dissimilar surface contacting faces located on opposite sides thereof and with air passages leading one from each of said faces and terminating in flattened openings at substantially the same level in opposite intermediate faces of said nozzle member whereby said nozzle member is of relatively low height, each of said openings being asymmetrical in design, with reference to a horizontal axis extending centrally of the opening and lying in the plane thereof, and of the same size and shape and disposed reversely with respect to each other, said suction conduit having an end portion generally of the size and shape of each of said openings and selectively receivable in either of said openings so that the proper surface contacting face of said nozzle will be in communication with said suction conduit.
3. The structure of claim 1 having latch means for retaining said nozzle member and suction conduit in assembled relation.
4. The structure of claim 1 having latch means for retaining said nozzle member and suction conduit in assembled relation and a pair of guarding projections, one at each side of said latch means.
